UNITED STATES PATENT OFFICE

EDWARD F. CLARK, OF NORTH ATTLEBORO, AND JULIAN H. MURDOCK, OF HOLBROOK, MASSACHUSETTS, ASSIGNORS, BY MESNE ASSIGNMENTS, TO CLARK LIGHTER CO., INC., OF NORTH ATTLEBORO, MASSACHUSETTS, A CORPORATION OF MARYLAND

POCKET VAPOR CIGAR LIGHTER

Application filed March 23, 1927. Serial No. 177,744.

Our invention is a pocket vapor cigar lighter, in which the lighter is made up of a metallic head carrying the working parts and a molded fuel container of non-metallic substance, such as hard or vulcanized natural rubber, synthetic rubber or synthetic resin, or the like, the two elements being hermetically locked together by a connection applied first in liquid form, and formed or 5 molded between the metallic and non-metallic elements and converted into a solid interlocking element integral with the molded box.

In the drawings:

15 Figure 1 is a side elevation of a cigar lighter;
Figure 2 is a central longitudinal section, parts being in elevation, of our cigar lighter, upon an enlarged scale;
20 Figure 3 is a detail, partly in section, of the upper end of the lighter, on the same scale as Figure 1;

Figure 4 is a bottom plan view of the lighter on the scale of Figure 2.
25 In the drawings 1 is the fuel container and 2 is the metal top plate, upon which are mounted the working parts of a lighter, such, for example, as is shown in Letters Patent of the United States 1,594,047, dated 30 July 27, 1926. As the lighter mechanism is no part of the present invention it will be unnecessary to further describe it.

The fuel container in our invention is to be made of hard vulcanized rubber or synthetic rubber or synthetic resin. Such materials are originally in plastic condition and while in this condition may be molded in any desired shape. For a container for the liquid fuel of a cigar lighter, which 40 fuel is usually alcohol, gasoline or other highly volatile fluid it is practically essential that any joints which exist should be perfectly sealed and this requirement, where the fuel container is of metal, requires very 45 close fit and is relatively an expensive method of manufacture with a certain portion of imperfect products, rendering the articles unsalable and unusable.

In our molded container there are no 50 joints or openings which are not absolutely

controllable and this without expensive fitting and riveting or other fastening.

The container 1 is molded as a five-sided box, the top of which is open. Upon the bottom of the box are provided metal shoes 55 11 having upon their upper surface undercut tangs 12. These shoes are applied while the container is in plastic condition, during the molding process and when the container is baked to harden the plastic material, the 60 shoes 11 become in effect integral with the container, the tangs 12 being embedded in the bottom wall of the container, which is made thick enough to receive the tangs 12 within its thickness. The tangs 12 are preferably 65 angular in cross section so that the shoes cannot work loose and turn upon the tangs as a pivot (see Fig. 4). In the centre of the bottom wall we provide a screw threaded filling aperture into which is screwed a plug 70 13 having a knurled disk 14 integral therewith, by which the plug 13 may be tightly screwed home.

The upper open end of the container 1 is closed and hermetically sealed as follows: 75 A metal top plate 2 is provided, upon which are mounted the mechanical working parts of the lighter which may be as desired. I have shown in the drawings the working elements of United States Patent 1,594,047. 80 In connection with the top plate 2 we employ a metal cup or connector element 22 which is provided with an aperture, registering with an aperture in the top plate 2, for the passage of the wick of the lighter which is 85 within the burner X. In Figure 3 we have shown the top plate 2 and cup 22 separated. In use the cup and top plate are brazed together to form a unitary structure, as shown in Figure 2. The depending sides or 90 flanges 23 of cup 22 are grooved, as at 24, and upon the outer surface of these depending sides is applied a rather thick film of viscous synthetic resin. The cup is then 95 passed into the open end of the container 1, the liquid resin being wiped back from the free edge of the cup, filling the groove 24, any surplus being carried beneath the projecting edges of the top plate 1 and exuded 100 over the upper edges of the container 1.

The structure now being subjected to a baking process, the liquid resin between the sides 23 and container walls hardens into a unit with the walls of the container 1, a portion of the resin forming an integral bead 15 filling the groove 24 around the outer surface of sides 23, so that the cup 22 and connected top plate 2 are locked to the container 1. The film of resin between the 10 side 23 of cup 22 and the inner surface of the container 1, from its fluidity is spread perfectly and with a perfect fit between the sides of the cup and the walls of the container, and is hardened by the baking process, along with the bead 15. The result is 15 a perfect joint, perfectly locked and perfectly fitted with no special care or expensive fitting process.

We have in the drawings indicated the 20 bead 15, which beginning as a liquid is by the curing process converted into a solid integral with the wall of container 1, by a solid black to call attention to that portion of the wall of container 1 which is added 25 as a liquid after the molding of the container and changed by a curing process into a solid condition integral with the container.

We claim:

1. In a cigar lighter, an open ended 30 molded fuel container; a bottom plate structure and a top plate structure, said top plate structure comprising a top plate having a wick hole therein and an inverted rectangular cup also having a wick hole therein brazed to the under side of said plate in such fashion that the wick holes in the top 35 plate and cup register, said cup having grooved faces acting as depending flanges adapted to fit within the open end of said 40 molded container; a bead adherent to the container wall adapted to fill the groove, lock the parts together and hermetically seal the joint between the container and faces.

2. In combination, with a cigar lighter 45 structure having its top plate structure sealed to a molded volatile container body, a top plate and a grooved inverted rectangular cup adapted to be brazed to the underside of said top plate to form the top plate 50 structure, a seal adapted to seal said cup to said body comprising a synthetic resin bead formed and baked in the groove in said cup and adherent to the molded body, and a thin layer of synthetic resin joining said cup 55 over each of its faces to the inner walls of said molded body.

3. In combination, with a cigar lighter structure having its top plate structure sealed to a molded volatile container body, 60 a top plate having a wick-hole therethrough, a grooved inverted rectangular cup also having a wick-hole therein adapted to registry with the wick-hole in the top plate and adapted to be brazed to the underside there- 65 of to form the top plate structure, a seal

adapted to seal said cup to said body comprising a synthetic resin bead formed and baked in the groove in said cup and adherent to the molded body, and a thin layer of synthetic resin joining said cup over each of its 70 faces to the inner walls of said molded body.

4. In combination, with a cigar lighter structure having its top plate structure sealed to a molded volatile container body, a top plate and a grooved inverted rectangular cup adapted to be brazed to the underside of said top plate to form the top plate structure, a seal adapted to seal said cup to said body comprising a bead of a cementitious material formed and baked in the groove in said cup and adherent to the molded body, and a thin layer of cementitious material joining said cup over each of its faces to the inner walls of said molded body.

5. In combination, with a cigar lighter 85 structure having its top plate structure sealed to a molded volatile container body, a top plate having a wick-hole therethrough, a grooved inverted rectangular cup also having a wick-hole therein adapted to registry 90 with the wick-hole in the top plate and adapted to be brazed to the underside thereof to form the top plate structure, a seal adapted to seal said cup to said body comprising a bead of cementitious material 95 formed and baked in the groove in said cup and adherent to the molded body, and a thin layer of cementitious material joining said cup over each of its faces to the inner walls of said molded body.

Signed at Boston, Massachusetts, this 100 twenty-second day of March, 1927.

EDWARD F. CLARK.
